UNITED STATES PATENT OFFICE

WILLIAM T. HORMES, OF CATONSVILLE, MARYLAND

DESIGN FOR A TABLE

Application filed November 12, 1929. Serial No. 33,424. Term of patent 7 years.

To all whom it may concern:

Be it known that I, WILLIAM T. HORMES, a citizen of the United States, residing at Catonsville, in the county of Baltimore and State of Maryland, have invented a new, original, and ornamental Design for a Table, of which the following is a specification, reference being had to the accompanying drawing, forming part thereof.

The element shown as extending trans-

versely and diagonally of the top of the table is an integral part of the table.

Figure 1 is a top plan view of a table, showing my new design. Figure 2 is a perspective view thereof.

I claim:

The ornamental design for a table, as shown and described.

WM. T. HORMES.
